(57) **CLAIM**

The ornamental design for a control module cover, as shown and described.

DESCRIPTION

FIG. 1 is a front perspective view of the control module cover, showing my new design;

FIG. 2 is a front view thereof;

FIG. 3 is a bottom view thereof;

FIG. 4 is a top view thereof;

FIG. 5 is a right side view thereof; and,

FIG. 6 is a left side view thereof.

The back of the control module cover is devoid of surface ornamentation.

The broken lines are included for the purpose of illustrating environmental structure and form no part of the claimed design.
